(57) **CLAIM**

The ornamental design for a tray for shipping electronic components, as shown and described herein.

DESCRIPTION

FIG. (1) is a perspective view of the bottom of the tray for shipping electronic components according to the invention; FIG. (2) is a top view of the tray for shipping electronic components according to the invention with an opaque shipping layer in place; FIG. (3) is a top view of the tray for shipping electronic components according to the invention; FIG. (4) is bottom view of the tray for shipping electronic components; FIG. (5) is a left side view of the tray for shipping electronic components according to the invention, the right side view being a mirror image thereof; FIG. (6) is a top end view of the tray for shipping electronic components according to the invention, the bottom end view being a mirror image thereof; and, FIG. (7) is a cross-section taken along lines 7-7 of FIG. 3 showing the contours of the present design.
